UNITED STATES PATENT OFFICE.

FRANK M. STEVENS, OF NEW YORK, N. Y., ASSIGNOR TO THE STEVENS LOCOMOTIVE AND MACHINE COMPANY, OF SAME PLACE.

DEVICE FOR CONVERTING MOTION.

SPECIFICATION forming part of Letters Patent No. 285,083, dated September 18, 1883.

Application filed July 7, 1883. (No model.)

To all whom it may concern:

Be it known that I, FRANK M. STEVENS, of the city, county, and State of New York, a citizen of the United States, have invented certain improvements in mechanical movements, adapted particularly but not necessarily for operating the valve-gear of steam-engines, of which the following is a specification.

My invention relates to a novel device for converting reciprocating into rotary motion. It may be applied to any mechanism where this conversion is desirable; but I have shown it in the accompanying drawings as applied to the rotation of the cam-shaft of a locomotive valve-gear. For this purpose I find it well adapted, as it reduces the weight of the parts as compared with the mechanisms usually employed for the conversion of the motion, and materially simplifies the construction.

In the drawings which serve to illustrate my invention, Figures 1 and 2 are side elevations, showing the operative parts in different positions. Fig. 3 is a front elevation of the mechanism, the cross-head guides being in section. Fig. 4 is a side elevation illustrating a modification, and Figs. 5 and 6 illustrate another modification.

Let A represent a locomotive-engine cylinder; B, the cross-head guides; C, the cross-head arranged to reciprocate in said guides, and D the connecting-rod which couples the cross-head to the wrist-pin in the driver. These may be of the usual kind.

E is the shaft, upon which are mounted the cams which impart the necessary motion to the slide-valve of the engine. I have not considered it necessary to show these cams, as they are well known. The shaft E is mounted rotatively in bearings a, which may be secured to the cross-head guides, and on the end of shaft E is secured a crank, F.

I will now describe the mechanism whereby alternate reciprocation of the cross-head imparts continuous rotary motion to crank F.

G is what I call a "reducing-lever," the upper end of which is coupled to the wrist-pin b of crank F.

H, I call a "lever-rod," one end of which is coupled to the lower end of lever G, and the other to a prolongation, c, of the cross-head.

I is what I call a "fulcrum-bar," one end of which is coupled to the reducing-lever between its ends, and the other to some fixed part at d—as a provision on the cross-head guides, for example. When the shaft E is not otherwise provided with weighty attachments sufficient to store up power enough to carry it over centers, it should be furnished with a fly-wheel. In the application of my device to a locomotive, however, the shaft E will have two cranks F, set at right angles, and there will be two sets of mechanism for converting the motion—one for each engine, as shown in Fig. 3. Thus both of the locomotive-engines will act on shaft E simultaneously and at right angles, and there will be no danger of its stopping on centers. Any tendency to this would, however, be counteracted by the cams on the shaft, which serve in some degree as balance-wheels.

I am able to dispense entirely with the fulcrum-bar I by employing the construction shown in Fig. 4; but this does not work quite so satisfactorily as that illustrated in the principal figures, for several reasons. In lieu of bar I, I provide the lever G with a slot, e, having a curve with a radius equal to the length of bar I; and in the slot e, I arrange a guiding-stud, f, set directly under the axis of the shaft E. As the lever G plays longitudinally, the stud plays along the slot, as will be well understood, and serves as a shifting-fulcrum.

The operation of the device is too simple to require more than a brief description.

Fig. 1 shows the cross-head at the end of its outstroke, and crank F at the end of its in-stroke, or on its inside center. As the cross-head moves in, (see arrow in Fig. 2,) lever-rod H carries back the lower end of the lever G, and by reason of the attachment of bar I to the lever the upper end of the latter turns crank F over outward. The swing of bar I and rod H permits the upper end of lever G to follow the circle traversed by pin b in the crank. The bar I and rod H are shown as arranged both on one side of shaft E; but this is not absolutely necessary.

In Figs. 5 and 6, I have shown another modification of my device, in which the reducing-lever G is fulcrumed at d, and the end of I is coupled to its upper end instead of at d. Fig. 100

5 shows the crank E standing at right angles to its position in Fig. 6.

I have said that my invention is a device for converting reciprocating into rotary motion; 5 but it is also adapted for converting rotary into reciprocating motion—as, for example, rotation of the shaft E will produce alternate reciprocation of the cross-head.

Having thus described my invention, I wish 10 it understood that I do not limit the application of my new device to the particular purpose herein described, as it may be employed for any purpose where it is desired to convert reciprocating into rotary motion, or vice versa.

15 I claim as my invention—

1. The combination, to form a mechanism for converting motion, comprising a shaft, E, provided with a crank, F, a reducing-lever, G, a bar, I, lever-rod H, and cross-head or other 20 reciprocating part, C, all constructed and arranged to operate substantially as set forth.

2. A mechanism or device for converting motion, comprising a shaft mounted to rotate and provided with a crank, a reciprocating part, a reducing-lever coupled at one end directly to the crank, and at its other end to the end of a lever-rod, the said lever-rod coupled to the reciprocating part, and a fulcrum-bar connected at one end to the reducing-lever, and the other to some fixed part or the specified equivalent of said fulcrum-bar, all arranged to operate substantially as set forth. 25 30

In witness whereof I have hereunto signed my name in the presence of two subscribing witnesses.

FRANK M. STEVENS.
